(57) **CLAIM**

The ornamental design for a hat rack, as shown and described.

DESCRIPTION

FIG. 1 is a right side perspective view of a hat rack showing my new design;

FIG. 2 is a rear, right side perspective thereof;

FIG. 3 is a front elevational thereof;

FIG. 4 is a rear elevational thereof;

FIG. 5 is a top plan thereof;

FIG. 6 is a bottom plan thereof;

FIG. 7 is a left side elevational thereof;

FIG. 8 is a right side perspective view of an alternate embodiment of the hat rack of FIG. 1 showing the broken line environmental structure of a hat;

FIG. 9 is a right side perspective view of an alternate embodiment of FIG. 8 shown without the broken line environmental structure; and,

FIG. 10 is a rear, right side perspective of FIG. 9.

The broken line showing a hat in certain of the Figures is for illustrative purposes only and does not form part of the claimed design.
